(57) CLAIM

The ornamental design of a cart mounted barbecue grill with elongated hood, as shown and described.

DESCRIPTION

FIG. 1 is a perspective view of a cart mounted barbecue grill with elongated hood showing our new design;

FIG. 2 is a left side elevational view thereof with the right side being a mirror image of that which is shown;

FIG. 3 is a front elevational view thereof;

FIG. 4 is a rear elevational view thereof; and,

FIG. 5 is a top plan view thereof.
